UNITED STATES PATENT OFFICE.

HENRY CHARLES SHORT, OF SOUTHALL, ENGLAND.

PORTABLE STAND FOR DISPLAYING GARMENTS.

1,426,225.

Specification of Letters Patent. Patented Aug. 15, 1922.

Application filed April 12, 1922. Serial No. 551,842.

To all whom it may concern:

Be it known that I, HENRY CHARLES SHORT, a subject of the King of Great Britain, residing at 39 Villiers Road, Southall, in the county of Middlesex, England, have invented certain new and useful Improvements in Portable Stands for Displaying Garments, of which the following is a specification.

10 The present invention relates to portable stands for supporting coats and other garments, and has for its object to provide a stand which shall be simple in construction, light in weight, and which when not in use may be disassembled or folded into a very compact space, to facilitate its transportation or storage, and easily erected so as to hold and display the coats or other garments.

The portable stand having the above qualifications obtained by this invention as hereafter described presents especial advantages for use of commercial travellers who, instead of being obliged to display their samples on tables in stock rooms, can without inconvenience carry with them such a portable stand in its folded condition and erect the same where required to display their samples to the best advantage and at the same time preserve their samples in better condition than if they were laid out in a folded condition as is now common.

According to this invention the portable stand comprises, when erected for use, a horizontal tubular member of a requisite length supported adjacent its ends by two pairs of legs, each pair being hinged about an axis at right angles to the length of the bar in such manner that the legs constituting each pair can be splayed apart and so maintained by a cross piece pivoted to one leg and adapted to engage the other leg of a pair by its opposite end, such engagement device being readily releasable.

Further each end of the horizontal bar 45 extending beyond the pivot of the adjacent pair of legs has pivoted thereto one end of a tie rod which can be turned downwards into an angular position, and means are provided upon the cross piece whereby the lower end 50 of the rod can be detachably fixed so that the legs are stayed and the whole structure rendered rigid. The garments can then be suspended from the horizontal bar by means of any well known coat hanger or like device. Such a construction can be readily 55 folded as hereafter described, the members

of the pairs of legs being brought together and folded about parallel with the horizontal bar and the tie rods similarly located.

The invention will be further described 60 with reference to an example of construction shown on the accompanying drawings, in which Fig. 1 is a side elevation of the portable stand in its open or erected position, Fig. 2 is an end view of the stand, and Fig. 3 is a view drawn to a larger scale, of a preferred means of attaching the supporting legs to the horizontal bar.

A stand constructed according to the present invention comprises a horizontal tubular bar 1, which bar 1 forms the upper member of the stand, supported adjacent each end by pairs of legs 2, 3 jointed to attachments on the horizontal bar 1, the said pairs of legs 2, 3 being stayed when erected 70 by tie rods 5, 6 connecting the horizontal bar 1 to cross pieces 7, 8, see Fig. 2, which latter serve to connect the legs together and hold them at a predetermined distance apart.

The pairs of legs 2, 3 are attached to the 75 bar 1 at a suitable distance from the ends thereof by sleeves 9 fixed to the bar 1, which sleeves 9 carry or have made in a piece therewith, lugs 10 which project downwards to receive bolts or pivots 11 passing at right 80 angles therethrough.

The upper ends of the pairs of supporting legs 2, 3 are constructed with lugs 12, 13 (Fig. 3) which are loosely carried on the 85 bolts 11, springs 14 being fitted on the bolts 90 11, between the lugs 10 of the sleeves 9 and the lugs 12, 13 of the legs, so as to prevent undesirable looseness of the joint while permitting the legs to be brought together or 95 splayed apart.

In the construction shown the cross pieces 7, 8 are each pivoted as at 15, Fig. 2, to one of the legs, and the opposite end of each cross piece 7, 8 is formed with a notch to take over a pin 16 on the opposite leg, upon 100 which pin the cross piece can be held by, say, a winged nut as shown.

The tie rods 5, 6 are each pivoted to the bar 1 as aforesaid, the construction illustrated showing each tie rod pivoted at 17 105 to a bracket on the bar 1 and having at its opposite end a shoulder 18 (or it may be a nut) which bears against a slotted angle bracket 19 when the end of the tie rod has been passed into the slot of the bracket, and the 110 tie rod is then clamped in position on the bracket by a winged nut as shown.

When the stand has been erected an additional bar, preferably tubular such as is shown by the dotted lines at 20, may be fitted and be supported by being notched 5 at its ends to engage the cross pieces 7, 8. In some cases where it is desired to erect a plurality of such stands one stand may be connected to another if so desired by socket pieces engaging and connecting the ends 10 of the horizontal bars 1 of such stands.

Such a stand can be rapidly disassembled for transport by releasing the winged nuts of the tie rods 5, 6 and removing same from the slotted angle brackets, and releasing and 15 detaching the ends of the cross pieces 7, 8 from the legs to which they are detachably fixed, and then the pairs of legs can be respectively brought together and folded up against the bar 1, the cross pieces 7, 8 brought 20 parallel with the legs, and the tie rods, 5, 6 also brought parallel with the bar 1, and the parts can then be strapped together. It will be observed that during this disassembling and folding no parts have been wholly de- 25 tached one from another, and therefore liability of the structure being rendered useless by loss of any of its parts is obviated.

What I claim as my invention and desire to secure by Letters Patent is:—

30 1. A portable collapsible stand for displaying garments; comprising in combination a horizontal bar from which said garments are to be suspended, a supporting device adjacent each end of said bar, each said 35 supporting device comprising a pair of supporting legs, means for loosely pivoting the upper ends of said pair of legs adjacent to each other and to said horizontal bar near one end thereof and about an axis extending 40 at right angles to said bar to allow said pair of legs to be splayed apart in planes at right angles to the axis of said bar to support the latter or be turned about said pivot to about parallel with said bar when not required for 45 use, a cross piece for each pair of legs, a pivot secured to one end of said cross piece to one leg of a pair, means for detachably connecting the other end of the cross piece to the other leg of the pair to hold said legs 50 splayed apart, a tie rod for each pair of legs, a pivot connecting one end of said tie rod to one end of said horizontal bar, said tie rod extending angularly downwards to said cross piece of the adjacent pair of legs, and 55 means for detachably connecting said end of said tie rod to said cross piece.

2. A portable collapsible stand for displaying garments; comprising in combination a horizontal bar from which said garments are to be suspended, a supporting device adjacent each end of said bar, each said supporting device comprising a pair of supporting legs, means for loosely pivoting the upper ends of said pair of legs 60 adjacent to each other and to said horizontal 65

bar near one end thereof and about an axis extending at right angles to the said bar to allow said pair of legs to be splayed apart in planes at right angles to the axis of said bar to support the latter or be turned about 70 said pivot to about parallel with said bar when not required for use, said means for jointing the upper ends of each pair of said legs to said horizontal bar comprising a sleeve fixed to said horizontal bar having a 75 downwardly projecting lug, a pivot passing through said lug at right angles to said bar, a lug on the upper end of each leg, each said lug having a hole formed therethrough through which said pivot loosely passes, said lugs of 80 said legs being located on opposite sides of said lug of said sleeve, springs located around said pivot between the lug of said sleeve and the lugs of said supporting legs, nuts on the ends of said pivot to retain the 85 lugs of said legs thereon, a cross piece for each pair of legs, a pivot to secure one end of said cross piece to one leg of a pair, and means for detachably connecting the other end of the cross piece to the other leg of the 90 pair to hold said legs splayed apart, a tie rod for each pair of legs, a pivot connecting one end of said tie rod to one end of said horizontal bar, said tie rod extending angularly downwards to said cross piece of the 95 adjacent pair of legs, and means for detachably connecting said end of said tie rod to said cross piece.

3. A portable collapsible stand for displaying garments; comprising in combination a horizontal bar from which said garments are to be suspended, a supporting device adjacent each end of said bar, each said supporting device comprising a pair of supporting legs, means for loosely pivoting the 100 upper ends of said pair of legs adjacent to each other and to said horizontal bar near one end thereof and about an axis extending at right angles to said bar to allow said pair of legs to be splayed apart in planes at right 105 angles to the axis of said bar to support the latter or be turned about said pivot to about parallel with said bar when not required for use, a cross piece for each pair of legs, a pivot to secure one end of said cross piece to 110 one leg of a pair, a screwthreaded pin fixed to and projecting from the opposite leg and a nut screwed on said pin, said cross piece having a notch to take over said screwthreaded pin on said leg and between the 115 latter and the nut on said pin to hold said legs splayed apart, a tie rod for each pair of legs, a pivot connecting one end of said tie rod to one end of said horizontal bar, said tie rod extending angularly downwards to 120 said cross piece of the adjacent pair of legs, and means for detachably connecting said end of said tie rod to said cross piece.

4. A portable collapsible stand for displaying garments; comprising in combina- 125

tion a horizontal bar from which said garments are to be suspended, a supporting device adjacent each end of said bar, each said supporting device comprising a pair of supporting legs, means for loosely pivoting the upper ends of said pair of legs adjacent to each other and to said horizontal bar near one end thereof and about an axis extending at right angles to said bar to allow said pair of legs to be splayed apart in planes at right angles to the axis of said bar to support the latter or be turned about said pivot to about parallel with said bar when not required for use, a cross piece for each pair of legs, a pivot to secure one end of said cross piece to one leg of a pair, means for detachably connecting the other end of the cross piece to the other leg of the pair to hold said legs splayed apart, a tie rod for each pair of legs, a bracket on each end of said horizontal bar, 20 a pivot connecting one end of said tie rod to said bracket, an angle bracket fixed centrally on the outer face of said cross piece, said bracket having a slot therein to receive the end of said pivoted tie rod, a collar on 25 said tie rod located above said bracket and a nut on the screwthreaded end of said tie rod below said angle bracket to clamp said tie rod to said bracket.

10 15 20 25 30

In witness whereof I have hereunto set my hand in the presence of two witnesses.

HENRY CHARLES SHORT.
